UNITED STATES PATENT OFFICE.

HENRY H. JOHNSON, OF AVOCA, IOWA.

COMBINED END-GATE AND SHOVELING-BOARD.

1,351,656.

Specification of Letters Patent. Patented Aug. 31, 1920.

Application filed October 12, 1917. Serial No. 196,195.

To all whom it may concern:

Be it known that I, HENRY H. JOHNSON, a citizen of the United States, residing at Avoca, in the county of Pottawattamie, State of Iowa, have invented certain new and useful Improvements in Combined End-Gates and Shoveling-Boards; and I do hereby declare the following to be a full, clear, and exact description of the invention, such as will enable others skilled in the art to which it appertains, to make and use the same.

This invention relates to improvements in wagon end gates and particularly to removable and convertible end gates.

One object of the present invention is to provide an end gate which is provided with a swinging portion serving as a door to facilitate the ordinary removal of the contents of the wagon.

Another object is to provide an end gate which is adapted to be so shifted as to provide a novel and efficient shoveling board.

The primary feature of the invention consists in making the gate with an upper section and depending legs spaced to produce an opening, and mounting in this opening a hinged door which in closed position fits between said legs and against the rear end of the bottom of the wagon body so tightly that a fine substance such as grain or sand may not leak out.

In carrying out this feature, a specific detail of the invention lies in the means for fastening the door closed against the legs of the upper section and holding said legs close against the wings of the end gate, so as to prevent the spreading of the wagon box under the weight of its load of granular material, which spreading is so often disastrous to the successful operation of end gates.

Other objects and advantages will be apparent from the following description when taken in connection with the accompanying drawing.

In the drawing:

Figure 1 is a rear elevation of the end gate and portion of the wagon on which said gate is carried, the gate being in closed position.

Fig. 2 is a vertical sectional view taken on the line 2—2 of Fig. 1.

Fig. 3 is an enlarged horizontal sectional view taken on the line 3—3 of Fig. 1.

Fig. 4 is a vertical sectional view on the

same line as that of Fig. 2, but showing the lower portion or door of the gate in open position.

Fig. 5 is a vertical longitudinal sectional view taken centrally through the end gate and portion of the wagon showing the gate in position for use as a shoveling board.

Referring particularly to the accompanying drawing, 10 represents the sides of the wagon box having strips 10' within their rear ends, 11 the bottom thereof. Movably disposed along the sides 10 and past the ends of the sill 11' of the wagon, are the side members or wings 12 of the end gate. Secured to these wings are the longer end boards of the gate, which boards are designated at 14' and herein called "legs," and between the legs are the shorter boards 14, all said boards being held together by means of the cleats or battens 13. The gate comprises an upper section A in the lower portion of which between said legs there is formed an opening for the reception of the lower section A' herein called a "door." Said door is made up of upright boards 16' adapted to stand in the plane of the boards 14, and a wide board or plank 16 secured across their outer faces and its ends lapping over onto the legs 14' as seen in Fig. 1. The door at its upper edge is hinged to the lower batten of the gate by means of the hinges 15, and may be swung upwardly and outwardly of the opening as clearly shown in Fig. 4 of the drawing. The upper section 90 has openings near its edges, and to its outer face are secured wear plates 17 having like openings. Through these project perforated studs 18 rigidly mounted on the inner faces of the body sides 10, and with their perforations are engaged the hooked ends of the rods 18' for holding the gate in elevated closed position, said rods being arranged to slide through said openings when the gate is swung downwardly on its pivot into the 100 position of a shoveling board, and at this time loops or eyes at the other ends of the rods bear against the wear plates and hold the board in such position. Secured to the central portion of the lower cleat is a hook 105 consisting of an upwardly extending strip of metal 19, a ring 20 being mounted on the swinging door A' by means of the strap 21 for engagement over the upper end of said strip to hold the door open or in elevated 110 position, whereby the contents of the wagon can be easily dumped.

- Inset into and secured to the inner face of each wing is a bracket having a plate 22' at right angles to its body and carrying a nut 22'' in its angle, and into said nut is 5 adapted to be screwed the threaded end of a screw or bolt 23 whose body is mounted through the leg 14 and has a shoulder 23' outside of it. Therefore by setting up said screw, the leg will be clamped against the 10 rear edge of the wing 12 and the rear end of the side 10 of the wagon box which said leg overlaps as seen in Fig. 3. The bolts are continued beyond their shoulders and formed with the T-shaped heads 24 for passage through open-ended slots 25 in the ends of the board 16 of the door and through like slots in wear plates 26 on its face. These heads are arranged to be turned transversely of the slots to hold the door in closed position against the legs when the wagon is in motion or not in use, or when the gate is 20 swung downwardly into the position for use as a shoveling board, as clearly seen in Fig. 5.
- 25 Secured to the rear face of the sill 11' is a strip 27 on which the lower end of the legs rest when the gate is in closed position, as shown in Figs. 1, 2, and 3, and on which the edges of the wings 12 rest when 30 the gate is in open position as a shoveling board, as seen in Fig. 5. Thus this strip cooperates with the lower end of the gate to form a pivot for the latter, obviating the necessity of connecting any part of the gate 35 to the wagon box. By unhooking the rods 18' from the lugs 18, the gate can be quickly and easily lifted from the wagon.
- With the parts standing closed as seen in Figs. 1 and 2, the simple turning of the 40 bolts with their heads 24 horizontal permits the door A' to swing open and readily dump a load of granular material which would then run out; but as long as the heads stand as seen in these views, the 45 door is clamped closed with its boards 16' in the opening against the legs 14' and resting on the strip 27 between the rear end of the bottom 11, and with the extended ends of its cross board 16 lapping the line between 50 its upright boards 16' and the legs 14' with the result that quite fine material such as sand will be retained without leakage. Also when the bolts are turned as described, their threaded ends enter the nuts 55 22'' and their shoulders 23' press the legs 14' close against the wings as seen in Fig. 3. With the lower ends of the wings hooked over the extremities of the strip 27, when the upper part of the structure is drawn in

by the studs 18 and the hooks of the rods 60 18', the legs 14' will be drawn closely against the rear edges of the sides of the wagon body and therefore will prevent leakage as well as spreading of said body under the weight of the load which often 65 occurs where the wagon body is an old one or the road is rough.

When the structure is let down as seen in Fig. 5, it becomes a shoveling board, and the then upper faces of the inner boards 16' 70 of the door are level with or perhaps a little below the upper face of the bottom 11 of the body, while their grain and that of the boards 14 and 14' and also the wings 12, is along the line in which a shovel would be 75 moved in loading or unloading the wagon. At this time the rods 18' support the outer portion of the structure, while the edges of the wings overlie the ends of the strip 27 and support its inner portion, and the door 80 is held in place by the hinges 15 and by the fact that it rests on the strip 27. When the structure is entirely disconnected from the wagon body, the rear end of the latter may be closed in any suitable manner as by 85 putting an ordinary gate down inside the strips 10'.

What is claimed is:

In an end gate structure for wagon bodies, the combination with an upper section closed at its upper portion and having legs at its sides extending downward, wings disposed at right angles to said legs and extending throughout their length, means pivotally connecting the lower ends of the 95 wings with the wagon body, means detachably connecting the upper portion of this section with said body, and a door hinged to said section and having upright boards for closing the space between said legs and a 100 cross board to lap said legs when the door is closed, the ends of such board having horizontal notches; of a bracket secured to each wing and having a nut, and a bolt passing through each leg and threaded at 105 its inner end to engage said nut, its body having a shoulder next outside the leg and projecting beyond the shoulder to engage one of said slots and its outer end having a T-head adapted to be set across the slot, 110 for the purpose set forth.

In testimony whereof I affix my signature in the presence of two witnesses.

HENRY H. JOHNSON.
